UNITED STATES PATENT OFFICE

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY

HEEL ASSEMBLING MACHINE

Application filed December 21, 1929. Serial No. 415,856.

This invention relates to heel assembling machines of the type in which two or more lifts or heel sections may be assembled to form a heel unit which may be itself either a complete heel or an assembled section to be combined with still another heel part. As exemplified herein, the machine may be arranged to facilitate the assembly of a heel base and a rubber heel to form a complete heel unit ready for attachment to a shoe.

An object of the invention is to produce an improved heel assembling machine which shall not only be capable of easy and rapid operation but shall be provided with such adjustments that it can be quickly adapted to operate upon heel sections of any size and, while insuring accurate register of the assembled heel sections, can be changed from one size to another in a minimum amount of time and with a minimum of effort, whereby increased production may be secured at less expense for machinery, labor and factory space than has heretofore been necessary.

With the above stated object in view an important feature of the invention consists in a double-deck heel holder comprising normally immovable side gages for positioning transversely one section of a heel and yielding gages mounted upon said adjustable gages for positioning transversely another section of said heel. The first-named gages are preferably adjustable to the size of one heel section to be dealt with, while the yielding gages which position the other heel section relatively to the first permit the second section to be inserted easily and quickly and insure that it shall be registered properly with the first. In the illustrated machine the unyielding side gages are combined with breast gages which partake of the adjustment of the side gages and provide for positioning a heel section longitudinally as well as transversely.

In another aspect the invention provides a double-deck heel holder comprising separate gages for the breast portions of two superposed sections of a heel, separate gages for the rear portions of said sections, and means for simultaneously adjusting the breast gages and the rear gages toward or from each other longitudinally of the heel. As

shown, one of the rear gages may be unyielding and, therefore, normally immovable, while the other may be yieldingly mounted upon it, serving to hold one of the heel sections against its breast gage.

Another feature of improvement which reduces the time required to change the machine to accommodate heel sections of different sizes consists in the provision of an expandible and contractile pressure applying pad, combined with means for adjusting the size of the pad to conform to different heels. By this means the usual necessity for providing a series of interchangeable pressure applying pads of different sizes is eliminated and the time required to change the machine is materially reduced. In the illustrated embodiment of the invention the pressure applying pad comprises a series of radially relatively movable pressing sections, and means is provided for adjusting said sections radially to vary the size of the pad. Preferably a single adjusting means is employed for this purpose and this may advantageously consist of a wedge element operated, for example, by a screw and arranged to engage and move all of the radially movable sections.

The above and other features of the invention, as well as the advantages derived from their use, will be better understood and appreciated from reading the following detailed description of one good practical embodiment of the invention, in connection with the accompanying drawings, in which

Fig. 1 is a view in side elevation, partly in central, longitudinal section, of a heel assembling machine embodying the invention;

Fig. 2 is a plan view of the blank assembling portion of the machine, showing the double-deck heel holder;

Fig. 3 is a section of part of the heel holder, taken on the line III—III of Fig. 2;

Fig. 4 is a front elevation of the pressure applying pad;

Fig. 5 is an underside plan view of the pad with parts broken away;

Fig. 7 is a front elevation of the heel holder.

Referring now to Figs. 1 and 2, 10 indicates the base and 12 the pressure pad carrying arm of a heel building machine of a well-known type.

The double-deck heel holder of the present invention is mounted upon a table 14 which is secured to the base 10 by bolts 16. 10 The holder comprises a work receiving plate 18 in which are provided guideways 20 for a rear gage 22 which is normally immovable, but is adjustable longitudinally of the heel holder.

15 The rear gage 22 is adapted to engage and position one section 24 of a two-section heel of which the second section is shown at 26. As illustrated, the heel sections 24 and 26 consist respectively of a rubber heel and a heel base which it is desired to secure together to constitute a complete heel ready for attachment to a shoe.

20 Yieldingly mounted upon the rear gage 22 is a second rear gage 28 which is slidably mounted upon said gage 22 and yieldingly pressed toward the front of the holder by a compression spring 30, the front end of which bears against a pin 32 screwed into the member 28 (see Figs. 1 and 3). It will be 25 apparent that the gage 28 will partake of any movement of adjustment of the member 22 but will be capable at all times of yielding relatively thereto, and the dimensions of the parts are such that the gage 28 will engage and position the second heel section 26. 30 Fore and aft adjustment of the above-described rear gages, longitudinally of the heel holder, is effected by one of the two sets of threads of a right and left screw 34, the rear end of which is swiveled in the stationary table 14, as shown at 36, in such a manner as to prevent longitudinal movement of the screw, while permitting it to be turned freely about its axis. The right-hand 35 threads 38 of the screw engage corresponding threads in a lug 40 (see Fig. 3) depending from the rear gage 22, through which lug the screw 34 passes.

40 The left-hand threads 42 of the screw 34 engage corresponding threads in a lug 44 depending from a slide 46 which is also guided for fore and aft longitudinal movement upon the table 14. The adjusting screw 34 is provided with a knob 48 by which 45 it may be turned in one direction or the other to adjust the rear gages 22, 28 and the slide 46 simultaneously toward or from each other.

50 Supported upon the slide 46, and movable therewith, is the breast and side gage mechanism which will now be described. Slides 50, 52 (see Figs. 2 and 6) are supported and guided for transverse movement upon the member 46 and are simultaneously adjusted 55 toward or from each other, transversely of

the heel holder, by a right and left screw 54 provided with a manually operable knob 56. Upon each of the slides 50 and 52 there is formed a breast gage 58 and a side gage 60, which are properly disposed to be engaged by, and to position, the breast and side edges of the heel section 24.

70 From the foregoing it will be apparent that rotation of the knob 48 will effect adjustment of the breast gages 58 and the rear gage 22 toward or from each other, the side gages 60 moving with the breast gages 58 and the yielding rear gage 28 moving with the rear gage 22. Independently of this adjustment rotation of the knob 56 will effect 75 transverse adjustment to the side gages 60 toward or from each other so that the holder may, by manipulation of the knobs 48 and 56, be adjusted accurately to fit and position the heel section 24.

80 For positioning the superposed heel section 26 in proper register with the first section 24 there are provided additional breast gages 62 which are carried by the slides 50, 52 and are guided to move freely through said 85 slides longitudinally of the heel holder. The outer ends of the gages 62 are turned downward, as shown at 64 (Fig. 3) and engage in a groove 66 in a transverse adjusting plate 68 operated by screw 70 threaded into the 90 slide 46. The screw 70 has a manually operable knob 72 and a disk 74 co-operating with a groove 76 in the under side of the plate 68 to effect the adjustment. Pins 78 secured in the slide 46 co-operate with diagonal slots 80 in the plates 68 so to guide the plate that it moves longitudinally of the heel holder when the adjusting screw 70 is operated, thus causing the breast gages 62 to be 95 adjusted longitudinally of the holder relatively to the gages 58, this adjustment not being affected in any way by transverse adjustment of said gages because the groove 66 is parallel to the adjusting screw 54. The purpose of adjusting the gages 62 relatively 100 to the gages 58 is to provide for positioning the heel sections 24, 26 either with their breast faces in alignment with each other or with one overhanging the other, as may be required by the nature of the work in hand.

115 For the transverse positioning of the upper heel section 26 there are provided side gages 82 which are pivoted at 84 upon the respective slides 50 and 52, and have at their outer ends blocks 86 (see Fig. 3) which engage freely in a transverse slot 88 formed in the top of a T-shaped member 90 which is guided for longitudinal movement in guideways 92 formed in the slide member 46. A pull spring 94 tends continually to draw the member 90 toward the front of the machine and thus yieldingly to close the side gages 82 inward toward each other. Since the slot 88 is also parallel to the screw 54, this operation 120 is unaffected by any change in adjustment of 125 130

said screw, the angular extent of the closing movement of the gages 82 about their pivots 84 being determined solely by an adjustable stop screw 96 threaded in the slide 46 and against the point of which screw the member 90 impinges.

From the foregoing it will be clear that, the proper adjustments having been made to provide for the sizes and shapes of the heel sections to be assembled, one section, as a rubber heel 24, may be placed in position between the gages 22, 58, 60 and then a second section, as a heel base 26, may be inserted between the yielding side gages 82 with its breast face against the breast gages 62, the rear gage 28 yielding to permit the heel base to be pressed down into engagement with the rubber heel and insuring that the said base will be positioned accurately against the breast gage 62, in accurate register with the rubber heel.

Ordinarily the heel sections to be assembled will have been previously coated with cement and all that is necessary to secure them together after they are properly registered with each other is the application of pressure. For this purpose there is provided the improved pressure applying pad which forms a part of the present invention and which will now be described.

Supported in the arm 12 is a vertical plunger 100 which is screw threaded, as shown at 102 and arranged for vertical adjustment by means of an internally threaded rotatable sleeve 104 having at its lower end a flange 106 upon which bears a heavy spring 108 the tension of which is adjustable by means of a sleeve 110 threaded into the arm 12. The spring 108 is so stiff that it will yield only when such excessive pressure is exerted as to endanger the machine. To the lower end of the plunger 100 is secured a head 112 having in its under side arcuate guideways for an intermediate supporting member 114 which is held up to the head 112 by bolts 116 surrounded by springs 118 and movable to a limited extent in slots 120 to permit the pressure pad to adjust itself angularly to the wedge of the heel.

The pressure applying pad itself comprises a base block 122 which is bodily adjustable forwardly and rearwardly of the intermediate member 114 by means of an adjusting screw 124. The under side of the block is provided with radial guides 126 in which are supported a plurality of radially movable pressure applying sections 128 (see Figs. 1 and 5). The general outline of the sections collectively is that of a heel and by moving the said sections radially inward or outward the size of the presser pad may be adjusted to conform to the size of the work to be dealt with.

Interposed between the respective sections 128 and retaining plates 130, which are se-

cured to the base block 122 by screws 132, are compression springs 134 which tend to contract the pressure applying pad by moving all the sections thereof radially inward. The inner portions of the sections 128 are 70 beveled or inclined, as shown at 136, and are engaged by a wedge member 138 at the lower end of a vertical screw 140 surrounded by a rotatable but vertically immovable nut 142 having in its periphery teeth 144 which are engaged by an adjusting screw 146, at the outer end of which is a manually operable knob 148 by the rotation of which expansion or contraction, and consequent adjustment in size, of the pressure applying pad may be effected to cause it to conform to the size to which the heel holder has been adjusted.

This last described adjustment having been made the arm 12 is drawn forward to the position shown in Fig. 1, whereupon it is automatically caused to descend by mechanism well-known in machines of this type and to apply the desired attaching pressure to the heel sections which have been assembled in the holder.

Having described the invention, what is claimed as new and desired to be secured by Letters Patent is:

1. In a heel assembling machine, a double-deck heel holder comprising normally immovable side gages for positioning transversely one section of a heel, and yielding gages mounted upon said immovable gages for positioning transversely another section 100 of said heel.

2. In a heel assembling machine, a double-deck heel holder comprising adjustable, but normally immovable, side gages for positioning transversely one section of a heel, and yielding gages mounted upon said adjustable gages for positioning transversely 105 another section of said heel.

3. In a heel assembling machine, a double-deck heel holder comprising adjustable side 110 gages for positioning transversely one section of a heel, and yielding gages mounted upon said adjustable gages and adjustable therewith for positioning transversely another section of said heel.

4. In a heel assembling machine, a double-deck heel holder comprising side and breast gages adjustable toward and from each other for positioning transversely and longitudinally one section of a heel, and yielding side 120 gages mounted upon said first-named gages and adjustable therewith for positioning transversely another section of said heel.

5. In a heel assembling machine, a double-deck heel holder comprising adjustable, but normally immovable, breast and rear gages for positioning longitudinally one section of a heel, separate breast gages for positioning longitudinally a second section of said heel, and a yielding rear gage mounted upon the 130

- first-named rear gage for holding said second section against its breast gages.
6. In a heel assembling machine, a double-deck heel holder comprising breast gages for positioning longitudinally one section of a heel, said breast gages being adjustable longitudinally of the heel, and breast gages for positioning a second section of said heel, the last-named gages being adjustable longitudinally of the heel with the first-named gages and independently adjustable longitudinally of the heel relatively to said first-named gages.
7. In a heel assembling machine, a double-deck heel holder comprising separate gages for the breast portions of two superposed sections of a heel, a gage for the rear portion of one of said sections, and means for simultaneously adjusting the breast gages and the rear gage toward or from each other longitudinally of the heel.
8. In a heel assembling machine, a double-deck heel holder comprising a gage for the breast portion of one of two superposed sections of a heel, separate gages for the rear portions of said sections, and means for simultaneously adjusting the breast gage and the rear gages toward or from each other longitudinally of the heel.
9. In a heel assembling machine, a double-deck heel holder comprising separate gages for the breast portions of two superposed sections of a heel, separate gages for the rear portions of said sections, and means for simultaneously adjusting the breast gages and the rear gages toward or from each other longitudinally of the heel.
10. In a heel assembling machine, a double-deck heel holder comprising side gages adjustable toward or from each other for positioning transversely one section of a heel, yieldingly closed gages mounted upon said side gages and adjustable therewith for positioning transversely a second section of said heel, and means for adjustably limiting the closing movement of the yielding gages independently of their adjustment toward or from each other.
11. In a heel assembling machine, the combination of a heel holder which is adjustable to accommodate heel sections of different sizes, and a pressure applying pad which is adjustable in size to correspond to various adjustments of the holder.
12. In a heel assembling machine, the combination of a heel holder having adjustable breast and rear gages, means for adjusting said gages toward or from each other, a pressure applying pad having adjustable breast and rear sections, and means for adjusting said sections of the pad toward or from each other to cause the pad to correspond to the holder.
13. In a heel assembling machine, the combination of a heel holder having adjustable
- breast and rear gages, means for simultaneously adjusting said gages toward or from each other, a pressure applying pad having adjustable breast and rear sections, and means for simultaneously adjusting said sections of the pad toward or from each other to cause the pad to correspond to the holder.
14. In a heel assembling machine, the combination of adjustable side gages for positioning a heel section transversely, means for simultaneously adjusting said gages toward or from each other, a pressure applying pad having side sections adjustable toward or from each other, and means for simultaneously adjusting said side sections of the pad to cause it to conform to the holder.
15. In a heel assembling machine, the combination of an expandable and contractile pressure applying pad, and means for adjusting the size of said pad to conform to heels of different sizes.
16. In a heel assembling machine, a pressure applying pad comprising a series of radially relatively movable pressing sections.
17. In a heel assembling machine, a pressure applying pad comprising a plurality of radially adjustable sections, and means for adjusting said sections radially to vary the size of the pad.
18. In a heel assembling machine, a pressure applying pad comprising a plurality of radially adjustable sections and a single means for simultaneously adjusting said sections radially to vary the size of the pad.
19. In a heel assembling machine, an expandable pressure applying pad comprising a plurality of radially movable sections each having an inclined inner face, and a wedge element arranged to engage the inner faces of said sections and move them radially to vary the size of the pad.
20. In a heel assembling machine, an expandable pressure applying pad comprising a plurality of radially movable sections, a wedge element arranged to move said sections radially to vary the size of the pad, and a screw operable to move the wedge element.
- In testimony whereof I have signed my name to this specification.
- ELMER R. POPE.
